(57) **CLAIM**

The ornamental design for a “chassis for radio control toy vehicle,” as shown and described.

DESCRIPTION

FIG. 1 is a perspective view of a chassis for radio control toy vehicle which embodies my new and original design therefor;

FIG. 2 is a front elevation view of thereof;

FIG. 3 is a rear elevation view thereof;

FIG. 4 is top plan view thereof;

FIG. 5 is a bottom plan view thereof;

FIG. 6 is a left side elevation view thereof; and,

FIG. 7 is a right side elevation view thereof.

The dashed lines in FIGS. 1-7 represent structural environment which forms no part of the claimed design.
